WILLIAM A. LEWIS, OF SPRINGFIELD, VERMONT, ASSIGNOR TO HIMSELF,
H. H. MASON, AND JOSEPH MESSINGER, OF SAME PLACE.

Letters Patent No. 63,731, dated April 9, 1867.

IMPROVED MOP-HEAD.

The Schedule referred to in these Letters Patent and making part of the same.

TO ALL WHOM IT MAY CONCERN:

Be it known that I, WILLIAM A. LEWIS, of Springfield, in the county of Windsor, and State of Vermont, have invented a new and improved Mop-Head; and I do hereby declare that the following is a full, clear, and exact description thereof, which will enable others skilled in the art to make and use the same, reference being had to the accompanying drawing, forming part of this specification.

This invention relates to a new and improved mop-head of that class in which the movable jaw is operated by a screw. The object of the present invention is to expedite the movement of said jaw, or give it a more rapid motion than hitherto; and to this end my invention consists in the application of the screws, one fixed on the end of the mop-handle, and the other, being a tubular one, provided with an internal thread, to work on the fixed screw, and also provided with an external thread, on which a nut connected with the movable jaw works, all being constructed and arranged to operate as hereinafter fully shown and described.

The accompanying drawing represents a side view of my invention.

A is a portion of a wooden handle, having a metal tubular screw, B, fitted permanently on its end, and C is a tubular rotary metal screw, having an internal thread to work on the screw B, and also having two projecting thumb-pieces *a a*, for the convenience of turning it. The screw C is also provided with an external screw-thread, *b*, on which a nut, D, is fitted; and to this nut the inner part of the movable jaw E of the mop-head is secured. This movable jaw may be of cast or wrought iron, of equivalent form, and provided with rounded corners, as shown clearly in the drawing. F is the fixed jaw, which may be cast or formed with the fixed screw B, and having a groove or recess in its outer surface to receive the outer side *c* of the movable jaw E. The two jaws E F are, or may be, constructed in the usual way, and therefore do not require a special description.

It will be seen from the above description that, by turning the screw C, the movable jaw E will be moved rapidly, as the movement of the screw C, on the fixed screw B, is combined with the movement of the nut D, on the screw C, in actuating said jaw; hence, the mop-cloth may be adjusted between the jaws and removed therefrom with the greatest facility.

Having thus described my invention, I claim as new, and desire to secure by Letters Patent—

The operating thumb-nut C, provided with external and internal screw-threads, in combination with the fixed screw B on the handle, and the sliding jaw F, substantially as and for the purpose described.

WILLIAM A. LEWIS.
